UNITED STATES PATENT OFFICE.

W. J. PRALL, OF POMEROY, OHIO.

IMPROVEMENT IN OIL-CANS.

Specification forming part of Letters Patent No. **59,066**, dated October 23, 1866.

To all whom it may concern:

Be it known that I, W. J. PRALL, of Pomeroy, Meigs county, and State of Ohio, have invented a new and useful Improvement in Oil-Cans; and I do hereby declare that the following is a full, clear, and exact description thereof, which will enable others skilled in the art to make and use the same, reference being had to the accompanying drawings, forming part of this specification, in which—

Figure 1 is a vertical section of my improved oil-can, taken through the line *x x*, Fig. 2, with the cover raised, and showing in red lines the cover closed. Fig. 2 is a top view of the same.

Similar letters of reference indicate like parts.

My invention has for its object to furnish a neat, durable, and convenient can for holding and handling carbon and lard oils; and it consists, first, in the oil-can, constructed and arranged as hereinafter more fully described; second, in the combination, with the oil-can, of a pump, arranged as described.

A is the body of the can, which is made of sheet-iron or tin, and may be of any desired capacity. B are handles or loops, attached to the sides of the upper part of the can, for convenience in handling it.

C is a drop-recess or perforated hanging shelf, formed or suspended in the upper part of the can, as shown in Figs. 1 and 2. The bottom of this drop C is perforated, so as to allow any oil that may drip or be spilled within it to flow back into the can. This recess also forms a convenient receptacle for the measures, tunnels, &c., by means of which the oil is handled, so as to have them always clean and convenient for use. Through the bottom of this recess is formed a hole, for convenience in cleaning out the can when necessary. This hole is closed with a perforated cap, D, as shown in the drawings.

The drop C extends about two-thirds across the top of the can, and the remaining part is covered over, as shown in Figs. 1 and 2. Through the central part of this covered portion is formed a hole, from which a tube, E, descends nearly to the bottom of the can A, as shown in Fig. 1. In this tube is placed an ordinary tin pump, F, of such a length as to reach to the bottom of the can, and at the same time to allow the cover G to shut down over it, as shown in red in Fig. 1. The nozzle of the pump F projects over the recess or drop C in such a way as to be convenient for placing the measure beneath it to receive the oil.

The pump F may also be used for transferring the oil from the barrel or cask to the can A. By placing the barrel or cask at the side of the can and inserting the barrel of the pump in the bung-hole of the cask, the oil may be quickly pumped into the said can.

The cover G is made of sheet-iron or tin, and is securely hinged to the upper part of the can, as shown in Fig. 1. It is also made with an upwardly-projecting recess, *g'*, to shut down over the upper end of the pump F; and said cover may be fastened with a clasp, H, and staple, I, so as to be fastened with a padlock when desired.

I claim as new and desire to secure by Letters Patent—

The perforated suspended drop C, adapted for the purpose described, perforated cap D, pump-receiving tube E, and cover G, with projecting recess *g'*, in combination with the body A, substantially as and for the purpose specified.

W. J. PRALL.
